ADJUSTABLE FLOWER POT HOLDER BRACKET OR THE LIKE

Richard L. Vogt, 1 Brookside Ave.,
Bellport, N.Y. 11713

Filed Feb. 14, 1967, Ser. No. 5,808

Term of patent 7 years

(Cl. D35—3)

FIG.1

FIG.2

FIG. 1 is a front view of a standard for an adjustable flower pot holder bracket, the bracket elements are omitted for ease of illustration;

FIG. 2 is a top plan view thereof; and

FIG. 3 is a side elevation thereof.

The broken line representation of the flower pot is shown for illustrative purposes only.

I claim:

The ornamental design for an adjustable flower pot holder bracket or the like, substantially as shown and described.
